PORTABLE OVEN FOR DRYING CABLE CONDUCTORS

John Boulware Doolittle and Charles Eastman
Morrison, Kansas City, Mo.

Application January 6, 1937, Serial No. 119,340

2 Claims. (Cl. 34—18)

This invention relates to a portable oven which is particularly adapted for drying insulated conductors contained in aerial cables which have been saturated with moisture and thereby caused 5 to break down.

It has been found that injuries, including sheath breaks, ring cuts and fatigue cracks, occur in aerial transmission cables and permit moisture to enter the cable sheath and cause insulation breakdown of the enclosed electrical conductors. This causes short-circuiting, grounding or other 10 damage to the conductors and it is necessary, in order to clear this condition, that the cable sheath be opened at the point of injury so that access 15 may be obtained to withdraw the damaged portions of the conductors so that they may be properly treated by the application of heat and thoroughly dried.

Accordingly, it is an object of this invention to 20 provide a portable oven which may be readily applied to a cable at the point of injury to supply heat whereby the moisture-saturated insulated conductors contained in the cable may be effectively and expeditiously dried. This and further 25 objects will be apparent from the following description, when considered in connection with the accompanying drawing in which one embodiment of the invention is illustrated.

Referring to the drawing, Figure 1 is a front 30 elevation of the device, a portion of the casing being broken away to show the cable and its insulated conductors positioned therein; Fig. 2 is an end view of Fig. 1, the end plates, illustrated in Fig. 5, being removed to show the interior of the 35 casing; Fig. 3 is a section taken on the line 3—3 of Fig. 1; Fig. 4 is an enlarged section of the wire grid taken on the line 4—4 of Fig. 2; and Fig. 5 is an elevational view of the pivoted end plates of the device.

The device disclosed in the drawing comprises 40 a casing which may be made from any suitable sheet metal. This casing is provided with an upper chamber 5 and a lower chamber 6. The upper chamber 5 may be of substantially rectangular shape and this chamber forms a drying oven for the cable conductors, which oven is preferably lined with asbestos. The lower chamber 6 is also shown as being of substantially rectangular formation and extends in a perpendicular 45 direction from the chamber 5. An intermediate chamber is provided between the chambers 5 and 6, and the walls 7 of the intermediate chamber interconnect the walls of the chambers 5 and 6.

The casing for the upper chamber 5 is provided

with a pivoted front panel portion 8 which is hinged at 9. This pivoted portion has a staple which cooperates with a hasp 10 secured to the cover or roof portion 11, whereby said pivoted panel may be locked in a closed position or released to an open position. The improved oven is adapted to be attached to a messenger wire 12, which supports the cable 13, at any point where the cable may be damaged. As shown in Figs. 1 and 2 the cover or roof portion 11 may be hooked 10 over the messenger wire.

The cable 13 is shown in Fig. 1 as having part of its sheath removed, disclosing the contained electrical conductors 14 in position in the drying chamber 5. The front panel 8 is shown in closed 15 position and the ends of the cable 13 are shown as extending beyond the ends of the drying chamber 5. The ends of said chamber are provided with adjustable plates or doors 15, 16 as more clearly shown in Fig. 5, which have their bottom 20 portions pivoted together at point 16 to the end walls of the chamber 5. The shapes of the plates 15, 15 are such that when in closed position their adjacent edges form a circular aperture which snugly engages about the sheath of the cable and the other portions of said plates fit against the 25 end walls of the chamber 5. With the front panel 8 and the plates or doors 15, 15 closed as described a closure is provided for the chamber 5 so that when heat is applied thereto, as will be presently 30 described, its loss is substantially prevented and air drafts are reduced to a minimum.

A longitudinal grille 17 may be applied to the bottom of the chamber 5 and may be supported by a ledge 18 extending inwardly from the walls of 35 said chamber. A handle 19 may be affixed to the cover or roof portion 11, to facilitate handling the device, and a flue 20 may be provided through said portion adjacent the handle to permit the escape of fumes.

The lower chamber 6 provides a compartment 40 for the reception of a can 21 or other container in which a supply of solidified alcohol, canned heat or the like may be stored. The can 21 is shown as being seated on the perforated bottom of the 45 chamber and in engagement with a spring clip 22 which is secured to the rear wall of the chamber. A door 23, hinged to the casing of the chamber 6, is provided for access to the can 21 and a pivoted fastener 24 serves to lock the door.

In the preparation of the cable for repairs, incision or removal of a section of the sheath is made at the point of injury where moisture has entered and caused a breakdown of the insulated conductors. When suitable access is had to the 50 55

conductors they are separated and fanned out as much as possible. The portable oven may be applied to the cable at this point by hooking the cover 11 over the messenger wire and so positioning the cable as to permit it to extend through the hinged end doors of the chamber 5. When the cable is in position these hinged doors are closed about the cable and the front panel is closed and locked by means of the hasp and staple. Light may be applied to ignite the contents of the can 21 which supplies heat to dry the moisture-saturated conductors. This heat circulates from the lower chamber through the upper drying chamber 5 in which the conductors 14 are located, and the drying process is continued until the conductors are shown by suitable tests to be thoroughly freed from moisture. The oven may be detached from the cable and messenger strand at this time and suitable soldering operations are performed on the cable sheath to restore its original condition.

While the arrangements of this invention have been illustrated as embodied in certain specific forms which have been deemed desirable, it will be understood that they are capable of embodiment in many and widely varied forms without departing from the spirit of the invention as defined by the appended claims.

What is claimed is:

30 1. In a device for drying the insulation of con-

ductors of a cable from which the sheath has been removed, a casing having two interconnected chambers disposed in perpendicular relation with respect to each other, means for holding insulated conductors in one of said chambers, said conductors having their sheath portions extending through the ends of the casing, a source of heat in the other chamber for heating the first-mentioned chamber and drying the moisture from the insulated conductors therein, and means pivotally associated with the ends of the casing and encircling the sheath portions of the cable for confining the heat within the casing.

2. In a device adapted to be attached to a messenger strand for drying the insulation of the conductors of the aerial cable suspended from the messenger strand, and from which the sheath has been removed, a casing having two interconnected chambers disposed in perpendicular relation with respect to each other, means for holding insulated conductors in one chamber of the casing, a source of heat in the other chamber of the casing for heating the first-mentioned chamber and drying the moisture from the insulated conductors in the first-mentioned chamber, and means associated with the casing for attaching it to a messenger strand to suspend it therefrom.

JOHN BOULWARE DOOLITTLE.
